UNITED STATES PATENT OFFICE.

FRITZ WALther AND GEORG WALther, OF ZELLA-MEHLIS, GERMANY.

AUTOMATIC FIREARM.

Application filed August 29, 1921. Serial No. 496,758.

To all whom it may concern:

Be it known that we, FRITZ WALther and GEORG WALther, citizens of the German Republic, residing at Zella-Mehlis 1, Germany, have invented certain new and useful Improvements in Automatic Firearms (for which we have filed applications in Germany, November 28, 1919; March 12, 1920, April 8, 1920, January 9, 1920; Austria, June 1, 1920; Czechoslovakia, June 21, 1920; Holland, June 2, 1920; Spain, July 17, 1920; Switzerland, May 31, 1920; France, June 30, 1920; Italy, June 29, 1920; Belgium, June 2, 1920; Sweden, February 15, 1921; England, February 25, 1921; Denmark, February 5, 1921, and Norway, June 1, 1921), of which the following is a specification.

Our invention relates to automatic firearms and has for its object to provide improved toggle mechanism for recoiling barrel guns.

According to the present invention, the bending of the toggle joint and the opening of the breech slide is effected by a lateral cam on the rear toggle lever mounted in the breech slide, which cam after the recoil of the receiver abuts on a spring controlled arm mounted on the wall of the receiver.

In order to bend the toggle joint controlled by a closing spring before the gun is used for the purpose of thereby withdrawing the breech block to such an extent as to enable a cartridge to be introduced into the barrel, the rear toggle lever is mounted on a pivot pin which can be turned by means of a crank, and so arranged that it does not in any way interfere with the automatic action of the gun, and can also stretch the toggle joint when the closing spring is no longer suitable for the purpose. Moreover in the present automatic gun the trigger is utilized for bringing about a complete stretching of the toggle joint before a shot is fired, when the said stretching cannot be effected by the closing spring alone, as may occur owing to the jamming of a cartridge.

In order that the invention may be clearly understood, we shall proceed to describe the same with reference to the various forms of construction shown by way of example in the accompanying drawings, wherein:

Figs. 1 to 7 show the device for operating the toggle joint for advancing the breech slide, with the barrel in the receiver.

Figs. 8 to 16 show the device for operating by hand the toggle joint lock, partly in

order to withdraw the breech block for the purpose of introducing a first cartridge and partly for the purpose of driving the breech block forward for closing the barrel.

Fig. 17 is a detail hereinafter referred to.

In said figures:

Fig. 1 shows the arrangement of the toggle joint closing device with the breech block closed, in the forward position of the barrel.

Fig. 2 is a longitudinal section through the rifle, with the barrel recoiling after firing, the toggle point being stretched.

Fig. 3 shows the position, the toggle lever being bent, just before the forward movement of the breech sleeve is completed, and just before the coming out of the spring-controlled hook.

Fig. 4 is a cross section on line X-X (Fig. 2).

Fig. 5 is a horizontal cross section on line XI-XI (Fig. 2).

Fig. 6 is a section on line XII-XII (Fig. 1).

Fig. 7 is a plan of the receiver according to Fig. 1.

Fig. 8 shows in front elevation, the device for operating the toggle joint by hand.

Fig. 9 is a longitudinal section on line XIII-XIII of Fig. 11.

Fig. 10 is a longitudinal section on line XIV-XIV of Fig. 11.

Fig. 11 is a horizontal section on line XV-XV of Fig. 10.

Fig. 12 is a vertical section on line XVI-XVI of Fig. 11.

Fig. 13 is a horizontal section similar to Fig. 12 showing the parts in their position after the release of the crank.

Fig. 14 is a vertical section on line XVII-XVII of Fig. 13, the handle being moved.

Fig. 15 shows the position of the crank handle in the position when it can be pulled out of the breech slide.

Fig. 16 shows, in longitudinal section, the position of the toggle-joint lever with the breech block withdrawn.

Fig. 17 is a detail view showing the toggle lever (partly broken away) separate from the breech casing.

The gun comprises a receiver or breech casing A and a breech slide B movable on the same which receives the barrel 1, and the breech block 2, the latter being operated by a toggle joint locking device 3, 4.

In order to hold fast in the gun the rear

member 4 of the toggle-joint 3, 4 during the return of the breech slide B and of the movable barrel 1 to the firing position, and thus to bring about the bending of the toggle-joint and therefore the opening of the breech block the rear toggle lever 4 is provided with a cam which, on the renewed advance of the breech slide B, finds an abutment on a spring-controlled arm mounted in the receiver A of the gun, and thus bends the toggle-joint and pulls back the breech block until the cam again passes out of reach of the spring-controlled arm during the renewed advance of the breech slide and barrel, and the toggle-joint is exposed to the action of the recoil spring, and therefore advances the breech block. In the described manner the bending of the toggle-joint during the withdrawing of the breech block brings about the ejection of the cartridge and the insertion of a new cartridge.

This arrangement is shown in a more detailed manner in Figs. 1 to 7.

With the breech block 2 engages at 61 the toggle-joint 3, 4 which has a pin 62 as the bending fulcrum, whilst the pin 63 of the rear toggle lever 4 is rotatable in the breech slide B. The toggle lever 4 has a lateral cam 64. In the wall of the receiver A is laterally pivoted in a groove or recess 66 an arm 65 which, by the action of a spring 67, is forced to project from said wall. When the slide B is moving back on the receiver A the spring controlled arm 65 is first forced into the wall by the cam 64 and then when the slide B arrives nearly at the end of its rearward movement and when the cam 64 has passed beyond the spring-controlled arm 65 the said spring-controlled arm 65 is forced out of the receiver A (Figs. 4 to 6) through the action of a cam face 68 on the slide. The spring-controlled arm is further subjected to the action of an oblique or cam edge 69 of a short end 70 of a bifurcated part 71 which is controlled by the barrel advance spring 72. The toggle-joint is exposed to the action of the recoil spring 73 which presses the pressure pin or rod 74 against a pin 75 of the toggle lever 4 and thus produces a stretching of the toggle-joint.

This operation of the parts is as follows:—

On a shot being fired, the slide B with the barrel 1 recoils, the barrel return spring 72 being compressed. By means of the stretched toggle-joint 3, 4 which recoils also, the recoil spring 73 is also compressed, that is to say the breech block remains closed. During the recoil of the slide B, the cam 64 passes the spring-controlled arm 65. After this has taken place, the cam face 68 of the slide B will force forward the spring-controlled arm 65, so that it will be brought within reach of the cam 64. The recoil of the slide B is now completed. The slide B

is provided with a stop 53 which strikes against a stop 56 on the receiver A. The barrel return spring 72 can now again become operative, and it will move forward the breech slide B with the barrel 1. The cam 64 of the toggle joint 3, 4 now strikes against the spring-controlled arm 65, so that the toggle-joint will be bent at its bending point 62 (Fig. 3) whereby the breech block 2 is pulled back. During the return of the breech slide B the fork 71 has been moved back also in simultaneously compressing the barrel return spring 72. This spring serves now for advancing the breech slide B. Shortly before the end of the advance of the breech slide B, the oblique edge 69 at the short end 70 of the fork 71, will again force the spring-controlled arm 65 into the receiver wall, so that the cam 64 will release the spring-controlled arm 65, so that the recoil spring 73 can again enter in action and by means of the pressure pin 74 acting on the rear toggle lever 4, stretch thus the toggle-joint 3, 4, that is to say lock the breech block 2.

The fork 71 presses with its front end against the stop 53 of the breech slide B. The released barrel return spring 72 will advance the breech slide B with the barrel 1. The action of the spring-controlled arm 65 on the cam 64, and therefore the stretching of the toggle-joint and the pulling back of the breech block 2 depends on the length and on the shape of the cam 64, as well as on the angular position which the cam 64 has relatively to the toggle lever 4. As all the parts, including the parts which control the toggle joint closing and the breech block, are mounted in the breech slide B and in the receiver A, and as these parts act directly on each other, any failure of these parts is less liable to happen. This arrangement facilitates the taking to pieces and the putting together of the gun without any special safety measures.

The cam 64 of the toggle-joint 3, 4 may also be used in conjunction with a stop A' on the receiver A (see Fig. 17) for the purpose of limiting the rearward movements of the barrel 1 and of the breech slide B. With this object in view the cam or cams 64 are provided at the toggle joint 4 with a rear stop surface 64^a so that, during the recoil of the barrel and when the toggle-joint 3, 4 is stretched, this stop surface 64^a strikes against the stop surface A'.

In order to load the gun for the first time, the breech block 2 must be withdrawn, that is to say the toggle-joint must be pressed back in opposition to the action of the closing spring 73. This is facilitated by the device shown in Figs. 8 to 16.

The pin 63 for the rear toggle lever 4 of the toggle joint 3, 4, is provided with a crank 82 with a handle 81 located in the

rear lateral wall of the breech slide B. The pin 83 is mounted in the breech slide B and is also provided with a hub 88 which plays in a bore or recess 86 of the wall of the breech slide. On the hub 83 is mounted a pin 84 which plays in a circular groove 85 of the front wall of the breech slide B. The bore 86 of the front wall of the breech slide has a recess 87 through which the pin 84 of the hub 83 can project when the crank 82 is turned backwards (see Fig. 15).

The hub 88 of the toggle lever 4 has a circular groove 89 with a stop shoulder 90. With the said cam face 90 engages a lip 91 on the pin 83 of the crank 82. On the crank handle 82 being turned to the right, the lip 91 which engages with the stop shoulder 90, will therefore turn the toggle lever 4 to the right so that the same pulls the breech block back. The crank handle is held in the inoperative position by a spring 92 with a projection 93 which engages with a groove 94 of the hand lever.

In order to enable the hand lever to be moved downwards in the direction of the arrow in Fig. 13, for the purpose of turning the toggle-joint, the projection 93 of the spring 92 must be pressed back.

This is possible owing to the fact that one edge 95 of the groove 94 is rounded off, so that when a pressure is exerted on the handle 81 in the direction of the aforesaid arrow, the spring projection 93 can be pressed back. If the toggle lever 4 is now turned by means of the lip 91 of the pin 83, which engages with the shoulder 90, that is to say if the breech block 2 is withdrawn, the crank handle 82 can be turned again into the initial position, Fig. 8, whereupon a cartridge can be introduced into the lock chamber.

If it is desired to take the gun to pieces, that is to say to pull the breech block 2 out of the breech slide B, the pin 83 together with the crank 82 must be removed. This can be done only when the crank handle is brought into the position shown in Fig. 15. The spring 92 must be therefore pressed so that its projection 93 gets out of the groove 94, as otherwise the sharp edge 96 of the groove 94 (Fig. 14) would prevent the taking to pieces of the gun.

In order to effect this the spring 92 has a projection 97 projecting behind the handle 81 and enabling the spring 92 to be turned back, that is to say said projection 97 is designed to press the projection 93 back into the front wall of the breech slide B. If the crank is now pressed in the direction of the arrow in Fig. 14 into the position in Fig. 15, so that the pin 84 of the hub is opposite the recess 87 of the front wall of the breech slide B, the crank 82 with the pin 83 can be withdrawn from the breech slide B, and the toggle joint 3, 4 will be released.

In order to bring the toggle lever back to the stretched position by means of the crank handle 82, which may be required when a cartridge which has perhaps a cardboard case, has jammed to such an extent that the closing spring 73 is unable to move the toggle joint lock 3, 4 and thus to force the breech block 2 completely forward, a stop is provided on the pin 83 opposite the lip 91. said stop consisting of a pin 98 which can be introduced through the button of the crank handle 82 and projects down to the plane of the circular groove 89. This pin forms a further stop at the face 99 of the circular groove 89 of the toggle lever, which is opposite the stop shoulder 90. The pin 98 can be removed from the crank 82, and in normal use of the gun it must be withdrawn from the crank 82, so that the toggle joint may work freely.

We claim:

1. A recoiling barrel gun comprising in combination a recoiling barrel, a receiver, a breech block, a breech slide and a toggle joint between the slide and block, a lateral cam on the rear member of said toggle joint, a spring controlled arm pivotally mounted on the wall of said receiver for stopping said lateral cam at the end of the recoil of the breech slide so that at the forward movement of the breech slide the said toggle joint is bent and the breech block is opened, a barrel return spring for returning said breech slide means controlled by said spring to push the said spring controlled arm back to release the said cam, and a recoil spring for stretching said toggle joint to close the breech block.

2. A recoiling barrel gun comprising in combination a recoiling barrel, a receiver, a breech block, a breech slide and a toggle joint between the slide and block, a lateral cam on the rear member of said toggle joint, a spring controlled arm pivotally mounted on the wall of said receiver for stopping said lateral cam at the end of the recoil of the breech slide so that at the forward movement of the breech slide the said toggle joint is bent and the breech block is opened, a barrel return spring for returning said breech slide, a bifurcated element controlled by said barrel return spring and designed to push the said spring controlled arm back to release the said cam, and a recoil spring for stretching said toggle joint to close the breech block, a cam face on said breech slide for bringing the said spring controlled arm into the path of said cam of the toggle joint.

3. In a recoiling barrel gun with toggle mechanism of the type described having front and rear links, means for stretching the toggle joint by hand comprising a pivot pin on the rear link engaging with said breech slide, a crank handle upon said pivot pin, a lip on said pivot pin, a removable

stop on said pivot pin opposite said lip, a hub on said rear link having a circular groove and a stop shoulder in said circular groove designed to arrest said removable stop, the crank handle being rotatable to the left so that the toggle joint is stretched.

4. In a recoiling barrel gun with toggle mechanism of the type described having front and rear links, means for stretching the toggle joint by hand comprising a pivot pin on the rear link engaging with said breech slide, a crank handle upon said pivot pin, a lip on said pivot pin, a removable stop on said pivot pin opposite said lip, a hub on said rear link having a circular groove and a stop shoulder in said circular groove designed to arrest said removable stop, the crank handle being rotatable to the left so that the toggle joint is stretched, and a spring for holding the said crank handle in the inoperative position, an extension of said spring, a projection on said spring projecting into a recess on said handle and disengageable therefrom by rotation of said handle.

5. In a recoiling barrel gun with toggle mechanism of the type described comprising in combination with the recoiling barrel, a breech slide having a circular groove in its side wall and with the toggle joint composed of a front link and of a rear link, a pivot pin on the rear link of the toggle joint engaging with said breech slide, a crank handle on said pivot pin having a groove, a hub on the rear link surrounding said pivot pin, a groove in said hub, a lug on said crank handle engaging with play in the groove of said hub, an end wall for said groove with which said nose comes in contact for turning the rear toggle lever, a hub on said crank, a pin on said hub engaging with the groove of said breech slide, and a spring controlled lever in said breech slide engaging with the groove of said crank handle retaining said handle in the middle position.

6. In a recoiling barrel gun with toggle mechanism of the type described comprising in combination with the recoiling barrel, a breech slide having a circular groove in its side wall and with the toggle joint composed of a front link and of a rear link, a pivot pin on the rear link of the toggle joint engaging with said breech slide, a crank handle on said pivot pin having a groove, a hub on the rear link surrounding said pivot pin

and a groove in said hub, a lug on said crank handle engaging with play in the groove of said hub, an end wall on said groove with which said lug comes in contact for turning the rear link, a hub on said crank, a pin on said hub engaging with the groove of said breech slide, and a spring controlled lever in said breech slide engaging with the groove of said crank handle retaining said handle in the middle position, a rounded edge of the groove of the crank handle for pushing back said spring controlled lever when the crank handle is being depressed, and a sharp edge of the groove of the crank handle for preventing the rotation of said crank handle beyond the dead point position.

7. In a recoiling barrel gun with toggle mechanism of the type described comprising in combination with the recoiling barrel, a breech slide having a circular groove in its side wall and a recess in said groove and with the toggle joint composed of a front link and of a rear link, a pivot pin on the rear link of the toggle joint engaging with said breech slide, a crank handle on said pivot pin having a groove, a hub on the rear link surrounding said pivot pin, a groove in said hub, a lug on said crank handle engaging with play in the groove of said hub, a shoulder on said groove with which said nose comes in contact for turning the rear link, a hub on said crank, a pin on said hub engaging with the groove of said breech slide, and a spring controlled lever in said breech slide engaging with the groove of said crank handle retaining said handle in the middle position, said pin of the hub of the crank handle being adapted to engage with said recess of the groove of the breech slide, a pin traversing said crank handle designed to depress said spring controlled lever so that the crank handle can be rotated beyond the dead point position until said pin of the hub stands opposite the recess in the groove of the breech slide.

In testimony whereof we affix our signatures in presence of witnesses.
